UNITED STATES PATENT OFFICE.

EDWARD W. MORGENTHALER, OF PAOLA, KANSAS.

DESIGN FOR A BOTTLE-GUARD.

SPECIFICATION forming part of Design No. 32,681, dated May 22, 1900.

Application filed April 20, 1900. Serial No. 13,672. Term of patent 7 years.

To all whom it may concern:

Be it known that I, EDWARD W. MORGENTHALER, a citizen of the United States, residing in Paola, county of Miami, and State of Kansas, have invented and produced a new and original Design for Bottle-Guards, of which the following is a specification, reference being had to the accompanying drawings, forming a part thereof.

10 Figure 1 represents a vertical sectional view of my new design for a bottle-guard. Fig. 2 represents a side elevation view of the same, and Fig. 3 represents a plan view.

The leading or material feature of my design consists in the configuration of the bottle-guard, as follows: The guard is made in the form of a ring provided on its inner periphery near the upper end with an inwardly-extending annular V-shaped flange A. The 15 portion of the inner wall below the flange A is perpendicular, and the lower end of the

ring terminates with an annular horizontal inwardly-extending flange C. The outer wall of the ring is convex in form, as indicated by B, the curve beginning at the top of the ring 25 and terminating near the lower end thereof.

My invention is applicable to various styles of guards for bottles, tumblers, and similar articles.

Having described my invention, what I 30 claim as new, and desire to secure by Letters Patent, is—

The design of a bottle-guard as herein shown and described.

In testimony whereof I have signed my 35 name to this specification in the presence of two subscribing witnesses.

EDWARD W. MORGENTHALER.
